UNITED STATES PATENT OFFICE

FREDERICK W. CUFFE, OF WAYNESBORO, VIRGINIA, ASSIGNOR, BY MESNE ASSIGNMENTS, TO EDISON GENERAL ELECTRIC APPLIANCE COMPANY, INC., OF CHICAGO, ILLINOIS, A CORPORATION OF NEW YORK

ONE-PIECE OVEN-UNIT FRAME AND UNIT

Application filed July 19, 1928. Serial No. 294,035.

This invention relates to improvements in oven unit construction, particularly of a type adapted for use in connection with electric ranges.

5 An object of this invention is to provide a heating unit for an oven comprising a main body portion consisting of one piece of material, suitably stamped or otherwise formed into a desired shape for removably position-
10 ing within the oven.

A further object of this invention is to provide an oven heating unit comprising a frame member made of a single piece of suitable material and formed in such a manner that the time required for pre-heating the oven is reduced to a minimum, and warping and twisting of the unit is practically eliminated.

Another object of this invention is to provide 20 a heating unit comprising a frame member of the lightest possible construction, the main portion of which is comprised of a single piece of properly shaped material having cross members attached thereto in such a manner as to allow for heat expansion and contraction and at the same time to prevent 25 doubling or bulging of the cross members which are provided with freely fitting refractory bushings for the purpose of sup-
30 porting the resistor or heating element.

Other objects of this invention will appear from the following detailed description of the device and as disclosed in the single sheet of drawings which is herewith made a part 35 of this application.

In the drawings—

Figure 1 illustrates a top plan view of the oven heating unit disclosing the main frame, cross bars and contactor springs in assem-
40 bled relationship.

Figure 2 represents a bottom plan view of Figure 1.

Figure 3 illustrates a sectional view of Figure 1, taken along line 3—3.

45 Figure 4 represents a sectional view of Figure 1, taken along line 4—4.

Figure 5 illustrates a sectional view of Figure 4, taken along line 5—5.

50 Figure 6 represents a sectional view of Figure 4, taken along line 6—6.

Figure 7 illustrates a perspective view of one of the cross members of the heating unit disclosing the folding contacts in assembled relationship therein.

The oven heating unit, according to this 55 invention, consists of a main frame section, made of any suitable material such as sheet metal, and stamped or formed into any desirable shape such as that disclosed in the Figures 3 and 4 of the drawing, wherein a 60 single piece of material has been formed having an outwardly extending flange portion 2, downwardly shaped side sections 3, and inwardly extending bottom portions 4, as clearly disclosed in Figure 3, while along one 65 side edge of portion 2 is provided a flange extension 5 for the purpose of supporting a terminal porcelain 6, through which suitable 70 terminal contact elements 7 are adapted to extend. The outwardly extending flange members 8, as clearly shown in Figure 4, are made of sufficient width to be slidably and removably positioned within an oven, particularly of the type common to electric 75 ranges and the like. Downwardly formed side members 9 extend from the flanges 8 and inwardly forming the bottom flange portions 10.

The terminal porcelain 6 may be suitably 80 supported in the frame by any proper means such as that disclosed in Figures 2 and 3, wherein a bracket member 11, made of sheet metal or otherwise, is supported by the flange extension 5 by means of machine bolts 12, or otherwise, the terminal porcelain 6 being 85 adapted to extend through an opening in the side 3 as a support for one end thereof, the other end of the porcelain terminal 6 being carried in the bracket 11.

90 Adjacent to the bracket 11 is a flange extension 13 from the bottom flange 4 for the purpose of allowing space for openings 14 therein which give easy access to the terminal contact screws 15, whenever it is required to bring the resistor or heating element 16 into electrical contact with the terminals 15, which connect with the floating contact members, or terminals 7.

95 In this invention it is preferred to construct the frame member, consisting of por-
100

tions 2, 3, 4, 8, 9, 10 and 5, of a single piece of material in order to prevent the warping or twisting of the units under heat, and to provide the lightest type of construction, also, for the purpose of reducing the time required for preheating the oven, to the lowest possible point.

The main frame having been constructed as above described is provided with cross members consisting preferably of two sections of material having flanged portions 17, 18, 19, and 20 extending at right angles to each other, two of the flange portions 17 and 19 being adjacently positioned and securely fastened together by means of rivets 21, or otherwise, it being understood that the structure of the cross bars may be of any desirable type without affecting the spirit of this invention.

At intervals along the cross bars are suitable openings 22 for the purpose of receiving freely fitting refractory supports 23 therein, which are made of refractory material, such as porcelain, and provided with openings 24 for slidably receiving the resistors 16.

The cross bars or members are held firmly in position within the main frame by means of tongue portions 25, preferably integrally formed from the bottom flange portions 10 of the frame. The tongue elements 25 are adapted to extend over and clamp the ends of the bar flanges 18 and 20 into firm but slideable relationship with the bottom flange extensions 10 of the frame, in such a manner that the cross bars or members will be allowed freedom of expansion due to the heating of the oven, it being understood that the cross bars are the first to become heated and that the means of holding these cross bars in position will prevent buckling and bulging thereof, as would clearly be the case if their ends were fastened to the frame without the possibility of some sliding action. The freely fitting refractory elements 23 and the terminal member 6 are located so as to insure perfect alignment of the various contacts with the resistors 16.

It will be understood that many changes and modifications may be made in the form of embodiment of this invention within the scope of the following claims without departing from the spirit of the invention.

What I claim is:

1. A heating unit for an oven comprising a main frame portion formed of a single piece of material, cross members slidably positioned in the main frame portion for expansion and contraction allowance due to heat, floating refractory bushings mounted in the cross members.

2. A heating unit for an oven comprising a main frame portion formed of a single piece of material, cross members slidably positioned in the main frame portion for expansion and contraction allowance due to heat,

floating refractory bushings mounted in the cross members, heating coils slidably positioned within the floating refractory bushings.

3. A heating unit for an oven comprising a main frame portion formed of a single piece of material, cross members slidably positioned in the main frame portion for expansion and contraction allowance due to heat, floating refractory bushings mounted in the cross members, heating coils slidably positioned within the floating refractory bushings, and a contact terminal mounted in the frame.

4. A heating unit for an oven comprising a main frame portion formed of a single piece of material, cross members slidably positioned in the main frame portion for expansion and contraction allowance due to heat, floating refractory bushings mounted in the cross members, heating coils slidably positioned within the floating refractory bushings, and floating contact members mounted in the frame for assuring proper alignment.

In testimony whereof I affix my signature.

FREDERICK W. CUFFE.
